Fig. 2.

UNITED STATES PATENT OFFICE.

FRED M. CLEAVELAND, OF WAKEFIELD, MASSACHUSETTS, ASSIGNOR TO FRED W. GREEN, OF IONIA, MICHIGAN.

STRAND-FEEDING MACHINE.

Application filed June 3, 1922. Serial No. 565,731.

To all whom it may concern:

Be it known that I, FRED M. CLEAVELAND, of Wakefield, in the county of Middlesex and State of Massachusetts, a citizen of the United States, have invented a new and useful Improvement in Strand-Feeding Machines, of which the following is a specification.

The invention relates to a strand feeding machine and especially one adapted to feed strands of rattan to a strand finishing or shaving machine like, for example, the machine shown and described in Letters Patent of the United States No. 216,723 of

June 24, 1879.

The object of the invention is to provide a mechanical feed for the strand into the finishing machine in place of the manual feed hitherto employed which calls for a high degree of operative skill and in any event is attended with considerable danger. In this connection it will be explained that a strand finishing or shaving machine, in order to properly function, is continually run at a high speed. Consequently a strand manually fed into the machine is violently jerked from the hands of the operator. This calls for a high degree of skill in feeding the strands and great care must be exercised for unless the strand be properly released very painful injuries will result. The essential object of the invention is to overcome these difficulties.

The extreme care required in a manual feeding of the strands necessitates their slow feeding and consequently the finishing or shaving machine functions for a relatively short part of its running time. Another object of the invention is to quicken the feed and thereby increase the operative efficiency of the finishing machine.

In fact the objects of the invention are to generally improve upon the manual feed.

The invention can best be seen and understood by reference to the drawings, in which—

Fig. 1 is a side elevation of the machine.

Fig. 2 is a view in cross section, certain of the parts being shown in elevation.

Fig. 3 is a plan of one of the units or segments later to be referred to, and

Fig. 4 is a cross section on line 4—4 of Fig. 3.

Referring to the drawings:

1 represents the end portions to a piece 55 or strand of rattan arranged in the present machine and, as will later be explained, about to be fed by it between the revolving feed roll 2 and cooperating presser roll 3 of a shaving machine like that referred to 60 in the aforesaid patent.

Arranged to run at right angles to the line of the feed of the strand into the rolls as aforesaid, is an endless carrier belt 4. This belt is made up of a number of individual parts or segments 5 pivotally connected by links 6 of suitable character.

The belt is supported by spaced sprocket wheels 7 and 8, respectively, around which the belt turns, 9 representing the upper running portion of the belt and 10 the lower or under running portion thereof. Each of the sprocket wheels 7 and 8 is carried by a shaft 11 which turns in bearings 12 supported by suitable standards, of which 13 represents the standard supporting the bearings for the sprocket wheel 7 and 14 the bearings for the sprocket wheel 8.

Each of the segments 5 of the belt presents an outer surface or face 15 along which is cut a groove 16 running lengthwise the segment at right angles to the path of the belt. Each of the grooves is adapted to receive the end portion of a strand to be finished, the strand being laid within it. To assist in the retention of the strand each groove is provided with inwardly-inclined or beveled side edges 17 and 18, respectively, by wedging contact with which the strand is held in place.

The strand portions 1 are laid in certain segments of the belt on the upper running portion 9 thereof lying back of a determinate station or point in front of the feed rolls of the shaving machine and the strand portions are fed laterally in substantially parallel lines to this point or station. In other words, each segment of the belt as it passes along the upper running portion thereof during the turning of the belt, will reach a determinate position where the groove 16 in the segment, or rather the strand 1 contained within the groove, will lie in front of the feed rolls of the shaving machine. As will presently be described, mechanism is provided by which the belt may be in-

termittently turned so that each segment of the belt will in turn reach the determinate position above referred to and dwell in such position a sufficient time to enable the strand borne by the segment to be detached therefrom and fed into the feed rolls of the shaving machine. The length of the belt and its arrangement is such that there will always be a number of segments on the upper running portion 9 of the belt back of the determinate position of the one segment from which the strand is fed, in order that the end portions of a number of strands may be laid in the grooves of such segments and eventually reach in turn the determinate position from which the strand is fed.

Reference will now be made to the mechanism for intermittently turning the belt and also to the mechanism which co-operates therewith and functions to disconnect the strand from a positioned segment and to feed it into the feed rolls of the shaving machine.

Fixed to the shaft 11 of the sprocket wheel 7 is a ratchet wheel 20. Arranged to turn upon the same shaft between the ratchet wheel 20 and one of the bearings 12 of the shaft is a feed crank 21. This crank carries a ratchet clutch member 22 pivoted to it by a pin 23 and held in operative engagement with the teeth of the ratchet wheel by a spring arm 24 fixed to the crank and backing the clutch member 22.

The feed crank 21 is operated from off a shaft 25 turning within a bearing 26 and operated by any suitable source of power, not shown. The shaft 25 carries a disk or web 27 bearing a crank pin 28 eccentrically arranged. Journalled to this pin is a rod 29 which connects with the feed crank 21 by means of a bolt and nut connection 30. At the point where the rod is connected to the arm the arm is provided with a slot 31 for purposes of adjustment. By these means the carrier belt is operated as the shaft 25 is turned, the proportioning, arrangement and adjustability of the parts being such that the belt will be turned intermittently just such distance as will successively bring each segment of the belt into the determinate position above noted in front of the feed rolls of the shaving machine and enable it to dwell in such position a sufficient time as will permit of the delivery of the strand borne by the segment into the feed rolls of the shaving machine.

The strand in any segment of the belt positioned in front of the feed rolls of the shaving machine is removed from the segment and fed into the feed rolls of the shaving machine during the period of the dwell of the segment as follows.

Secured to the crank pin 28 of the shaft 25 is a web 32 having a crank pin 33 ec-

centric to the shaft and located diametrically opposite the pin 28. Journalled to the pin 33 is a link 35 pivotally connected to the lower end of a bar 36 slidably arranged in a vertical guide 37 on a standard 38, the arrangement being such that the bar 36 is movable endwise up and down within the guide as the crank shaft is turned. The bar 36 lies adjacent the side of the belt and has secured to it an arm 39 which extends crosswise beneath the upper running portion 9 of the belt and immediately below the point or station occupied by that segment from which the strand is to be delivered. Secured to the arm 39 are sets of spaced fingers 40 and 41 each set bearing between them a grooved roll 42. The fingers extend upwardly by the respective ends of the positioned segment and the arrangement is such that when the bar 36 is lifted the wheels 42 will be brought into contact with the strand and lift it out of the segment. On the return movement of the bar 36 the fingers and rolls 42 carried by them will drop into an out of the way position below the top running surface of the belt or where they will not interfere with the strands carried by the belt during its forward movement.

Arranged upon the forward end of the arm 39 on the delivery side of the belt is a spring arm 43. Carried by this arm is a grooved idler roll 44. This roll occupies a position in exact alignment with the groove 16 in that positioned segment from which the strand is delivered, the roll lying just below the line of the strand which is placed within the segment with the end thereof extending so far as to lie above the roll. Located above the roll 44 is a feed roll 45 driven by a pulley 46, both roll 45 and pulley being arranged upon a shaft 47 which turns in bearings 48 on a frame extension 49 to the standard 13. In the operation of the machine the feed roll 45 is driven at a speed substantially equal to that of the feed rolls to the shaving machine to which the strand is delivered. When the arm 39 is raised for lifting the strand out of the segment, the roll 44 will also be lifted and thereby lift the end of the strand into contact with the feed roll 45 which thereupon feeds the strand into the feed rolls of the shaving machine. All the strands are so placed in the segments that their ends will project sufficiently to lie above the roll 44 when the strands are brought into position for discharge so that they may be engaged by this roll and fed by the roll 45 as aforesaid.

It will also be observed that when the strand is lifted out of the positioned segment it is held in proper aligned position to be fed by the roll 45 into the feed rolls of the shaving machine. The strand will then rest upon the rolls 42 with

the spaced ends of the sets of fingers projecting above the rolls 42 acting as lateral guides for the strand as it is fed.

In the running of the machine the operator will keep the segments on the upper running portion 9 of the carrier lying back of the strand delivery station filled with strands, no further manual work being required, each strand being then taken care of in turn by the machine.

Inasmuch as the strands vary in length, it is necessary that the machine be so timed that the dwell of the carrier will be so long as to permit of the feeding of the longest strands from any segment of the carrier positioned as aforesaid.

Having thus fully described my invention, I claim and desire to secure by Letters Patent of the United States:

- 20 1. In a strand-feeding machine, the combination with an operating mechanism, of a movable carrier for receiving and holding the end portions of a number of strands arranged separate from one another on substantially parallel lines and applied to the carrier to extend crosswise it with permitted detachability therefrom, means for intermittently operating the carrier whereby each of the strands carried by it will be moved laterally to reach and occupy in turn a determinate position with dwell of the carrier when the strand is occupying such determinate position, means for detaching each strand positioned as aforesaid from the carrier during the dwell of the carrier, and means for feeding the detached strand.
- 25 2. In a strand-feeding machine, a movable carrier for receiving and holding the end portions of a number of strands arranged separate from one another on substantially parallel lines and applied to the carrier to extend crosswise it with permitted detachability therefrom, means for intermittently operating the carrier whereby each of the strands carried by it will be moved laterally to reach and occupy in turn a determinate position with dwell of the carrier when the strand is occupying such determinate position, means for detaching each strand positioned as aforesaid from the carrier during the dwell of the carrier, and means for feeding the detached strand.
- 30 3. In a strand-feeding machine, a movable carrier for receiving and holding the end portions of a number of strands arranged separate from one another on substantially parallel lines and applied to the carrier to extend crosswise it with permitted detachability therefrom, means for intermittently operating the carrier whereby each of the strands carried by it will be moved laterally to reach and occupy in turn a determinate position with dwell of the carrier when the strand is occupying such determinate position, means for detaching each strand positioned as aforesaid from the carrier during the dwell of the carrier, and means for feeding the detached strand.
- 35 4. In a strand-feeding machine, the combination with an operating mechanism, of a movable endless carrier having a number of connected strand-bearing units, each of said units having an open groove with inclined sides extending across the face of the unit and in which the end of a strand is contained, means for intermittently operating said carrier whereby each of its units and strand carried by it will reach and occupy in turn a determinate position on the upper running portion of said carrier during the operation thereof with dwell of the carrier when said unit and strand carried by it is occupying said determinate position, means for lifting each strand positioned as aforesaid out of the groove in the unit containing it during the dwell of the carrier, and means for feeding the detached strand.
- 40 5. In a strand-feeding machine, the combination with an operating mechanism, of an endless carrier having a number of connected strand-bearing units, each of the units being adapted to receive and hold with permitted detachability the end of a strand applied to the unit to extend crosswise it, means for intermittently operating the carrier whereby each of its units and strand carried by it will reach and occupy in turn a determinate position in the path of the carrier during the operation thereof with dwell of the carrier when said unit and strand carried by it are positioned as aforesaid, means for detaching each strand positioned as aforesaid from the unit carrying it, loosely holding the strand in position for feeding and guiding the strand during its feeding, means for intermittently operating said last-named means to function during the dwell of the carrier, and means for feeding the detached strand.
- 45 6. In a strand feeding machine the combination comprising a driven feed roll, a movable carrier for receiving and holding the end portions of a number of strands arranged separate from one another and applied to the carrier to extend crosswise the carrier and be detachable therefrom, means for supporting and arranging the carrier whereby each strand carried by it will in turn reach and occupy a determined position in the path of the carrier and adjacent said driven roll during the operation of the carrier, means for operating the carrier whereby each strand carried by it will in turn be positioned as aforesaid with accompanying dwell of the carrier, means for detaching each strand positioned as aforesaid
- 50 115
- 55 120
- 60 125
- 65 130

from the carrier during the dwell of the carrier and means for moving the detaching strand into contact with said driven feed roll.

7. In a strand feeding machine, the combination comprising a driven feed roll, an endless carrier for receiving and holding the end portions of a number of strands separately arranged and extending crosswise the carrier, means for supporting and arranging the carrier whereby each strand carried by it will in turn reach and occupy a determinate position in the path of the carrier and adjacent said roll during the operation of the carrier, means for operating the carrier whereby each strand will in turn be positioned as aforesaid with accompanying dwell of the carrier, and means for detaching each strand positioned as aforesaid from the carrier during the dwell of the carrier, retaining the detached strand in position to be fed and moving the same into contact with said feed roll whereby it will be fed thereby.

8. In a strand-feeding machine, the combination comprising a driven feed roll, an end-

less carrier for receiving and holding the end portions of a number of strands separately arranged and extending crosswise the carrier with ends projecting laterally therefrom whereby each strand carried by it will in turn reach and occupy a determinate position in the path of the carrier adjacent said feed roll during the operation of the carrier, means for intermittently operating the carrier whereby each strand will in turn be positioned as aforesaid with accompanying dwell of the carrier, means adapted when operated to detach each strand positioned as aforesaid from the carrier during the dwell of the carrier, hold the detached strand in position for feeding and guide the strand during its feeding, means for operating said last-named means intermittently to function during the dwell of the carrier, and means carried by said strand-detaching, holding and guiding means for moving the strand into contact with said feed roll whereby it will be fed thereby.

FRED M. CLEAVELAND.
